United States Patent

Des. 242,449
Patented Nov. 23, 1976

242,449

WRITING PEN

Rudi Jahraus, Keltern-Ellmendingen, Germany, assignor to Moriz Hausch GmbH

Filed Mar. 17, 1975, Ser. No. 558,788

Claims priority, application Germany Oct. 11, 1974

Term of patent 14 years

Int. Cl. D19—06

U.S. Cl. D19—45

FIG. 1

FIG. 2

FIG. 3

FIG. 4

FIG. 5

FIG. 1 is a top plan view of a writing pen showing my new design;

FIG. 2 is a front elevational view;

FIG. 3 is a right side elevational view with the point in an extended position;

FIG. 4 is a rear elevational view of FIG. 1; and

FIG. 5 is a left side elevational view thereof.

I claim:

The ornamental design for a writing pen, substantially as shown and described.
